UNITED STATES PATENT OFFICE.

GEORGE HUNTER, OF ELGIN, ILLINOIS, ASSIGNOR, BY MESNE ASSIGNMENTS, TO ROYAL E. ROBBINS, OF BOSTON, MASS., AND THOS. M. AVERY, OF CHICAGO, ILLINOIS, TRUSTEES.

STEM-WINDING AND HAND-SETTING ATTACHMENT FOR WATCHES.

SPECIFICATION forming part of Letters Patent No. 312,856, dated February 24, 1885.

Application filed August 28, 1884. (No model.)

To all whom it may concern:

Be it known that I, GEORGE HUNTER, of Elgin, in the county of Kane, and in the State of Illinois, have invented certain new and useful 5 Improvements in Stem-Winding and Hand-Setting Attachments for Watches; and I do hereby declare that the following is a full, clear, and exact description thereof, reference being had to the accompanying drawings, in 10 which—

Figure 1 is an enlarged perspective view of my push-pin and its connections separated from each other. Fig. 2 is a like view of the same combined. Fig. 3 is a longitudinal section of the stem or pendant portion of a watch-case containing my invention, the push-pin being in position for operating the winding mechanism; and Fig. 4 is a like view of the same with said push-pin in position for actuating the hands-setting mechanism.

Letters of like name and kind refer to like parts in each of the figures.

My invention is an improvement upon a like invention for which Letters Patent No. 25 192,425 were issued upon the 26th day of June, 1877; and it consists, principally, as an improvement in stem-winding and hand-setting watches, in a push-pin which is adapted at its inner end to engage with the winding and 30 hands-setting train, and is provided with a retaining-spring that is attached directly to, is adjustable lengthwise of, and moves with, said push-pin, in combination with the chambered stem or pendant of a watch-case, substantially as and for the purpose hereinafter 35 specified.

It consists, further, in combining with the chambered stem or pendant of a watch-case a ring of hard metal, which is secured within 40 said chamber and is adapted to engage with the retaining-spring of a removable push-pin, substantially as and for the purpose hereinafter shown.

It consists, finally, in the combination of 45 the push-pin, the adjustable retaining-spring, the chambered stem or pendant, and the engaging-ring, substantially as and for the purpose hereinafter set forth.

In the annexed drawings, A represents the

center-band, B the stem or pendant, C the 50 bow, and D the case-spring, of a watch-case of usual construction.

The stem or pendant B is provided with the usual axial opening, b, that at its inner end has a slightly greater diameter than the push-pin 55 or winding-stem arbor E, which is to be used therein, while the outer portion of said opening is considerably increased in diameter, and at or within its outer end contains a ring, b', constructed from hard metal, that is secured 60 in place by burnishing, or other suitable means, and forms at such point a rounded shoulder. The push-pin or winding-arbor E has such diameter of its inner portion as to enable the same to be loosely contained within 65 in the corresponding part of the stem-opening b, and such length that when said inner end is resting upon the spring D its outer end will project the required distance from out of the stem B, and at such point receive a 70 crown, F.

At a point near the longitudinal center of the push-pin E is a threaded enlargement, e, upon which is placed a U-shaped spring, G, that at its inner end has a threaded opening, 75 g, which passes over and engages with said enlargement e. The outer ends of the arms g' of the spring G are slightly spread, so that their outer faces at such point will have a greater spread than the inner diameter of the 80 ring b', and within such faces is provided a circumferential groove, g'', that corresponds in transverse size and shape to the inner face of said ring b'.

As thus constructed the spring G operates 85 by engagement of its outer ends, or of the groove g'', with the ring b' to hold the push-pin E in position within the stem or pendant B, while permitting of its ready withdrawal therefrom when a sufficient force is exerted 90 in an outward direction.

In adjusting the push-pin E to the watch-case, the spring G is moved longitudinally until its outer ends will bear lightly against the lower side of the ring b', when the inner end 95 of said push-pin has a bearing upon the spring D, by which means all rattle from end motion of said push-pin is avoided.

The push-pin E is used for the movement of the spring G precisely as in ordinary cases, and by the engagement of its inner end with winding and hands-setting mechanism may be used in any usual manner for winding the mainspring and setting the hands, while by withdrawing said push-pin until the spring-grooves g^2 engage with the ring b' said push-pin, while held in such position, will be free to revolve.

The partial withdrawal of the push-pin E may be utilized for throwing the hands-setting train into position for use, and also enables the watch-movement to be easily removed from or placed within the case.

Having thus fully set forth the nature and merits of my invention, what I claim as new is—

1. As an improvement in stem-winding and hand-setting watches, a push-pin which is adapted at its inner end to engage with the winding and hands-setting train, and is provided with a retaining-spring that is attached

directly to, is adjustable lengthwise of, and moves with, said push-pin, in combination 25 with the chambered stem or pendant of a watch-case, substantially as and for the purpose specified.

2. In combination with the chambered stem or pendant of a watch-case, a ring of hard 30 metal which is secured within said chamber and is adapted to engage with the retaining-spring of a removable push-pin, substantially as and for the purpose shown.

3. The combination of the push-pin, the 35 adjustable retaining-spring, the chambered stem or pendant, and the engaging-ring, substantially as and for the purpose set forth.

In testimony that I claim the foregoing I have hereunto set my hand this 21st day of 40 July, A. D. 1884.

GEORGE HUNTER.
